Primary Examiner — April Rivas(74) *Attorney, Agent, or Firm* — Inskeep IP Group, Inc.(57) **CLAIM**

I claim the ornamental design for a toolbox, as shown and described.

DESCRIPTION

FIG. 1 is a front view of a toolbox showing my new design;
FIG. 2 is a rear view thereof;
FIG. 3 is a left-side view thereof;
FIG. 4 is a right-side view thereof;
FIG. 5 is a top view thereof;
FIG. 6 is a bottom view thereof;
FIG. 7 is a front perspective view thereof; and,
FIG. 8 is a rear perspective view thereof.
The broken lines shown in the drawings are for the purpose of illustrating portions of the toolbox that form no part of the claimed design.

1 Claim, 8 Drawing Sheets(56)
